CHARLES TAYLOR AND BERTRAM H. SAUNDERS, OF PATERSON, NEW JERSEY.

PILING-MACHINE.

1,342,190.

Specification of Letters Patent.

Patented June 1, 1920.

Application filed December 1, 1919. Serial No. 341,571.

To all whom it may concern:

Be it known that we, CHARLES TAYLOR, a subject of the King of Great Britain, and a resident of Paterson, Passaic county, New Jersey, and BERTRAM H. SAUNDERS, a citizen of the United States, and a resident of Paterson, Passaic county, New Jersey, have invented a new and useful Improvement in Piling-Machines, of which the following is 10 a full, clear, and exact description.

Our invention relates to improvements in piling machines for piling fabrics. Our invention is especially intended for improvements in piling machines which take long 15 ropes of fabric and pile them in even compact layers so that the fabric will not become badly twisted and tangled, and so that it can be readily withdrawn from the pile. Our machine is particularly adapted for 20 handling long ropes of fabric, and especially textile fabric, and pile them in compact symmetrical layers, and for this reason the machine can be readily adapted to piling such fabrics in keirs or other receptacles in 25 which the fabric is treated in bleaching or other liquors, and by our arrangement the fabric can be rapidly, evenly, and compactly piled in such a vessel in such a way that all parts of the fabric will receive proper treatment 30 from the liquor and yet in such a manner that the fabric can be readily withdrawn after treatment. In attempts to do this work by machinery, difficulties have arisen sometimes because the machinery has been too intricate and fragile to withstand this rather 35 coarse operation, and because machine piling has had a tendency to cause the fabric to become twisted and tangled so that it is not properly treated, and furthermore, when so twisted and tangled it cannot be withdrawn without injury. Attempts have been made 40 to pile the fabric in spiral layers, such spirals running in and out from the center to the circumference of the pile, and this idea 45 is especially objectionable because the fabric becomes so badly twisted and tangled that it cannot be withdrawn without injury, and sometimes without actually cutting it up to permit its removal. Our invention overcomes the above difficulty, and it is further 50 intended to produce a very simple and strong machine having few parts, so that it can be depended on to do its work properly, and furthermore, the invention is intended 55 to provide means by which the operative parts of the machine can be readily raised

and lowered to adapt it to special work, as will be hereinafter described.

Reference is to be had to the accompanying drawings forming a part of this specification, in which similar reference characters indicate corresponding parts in all the views.

Figure 1 is a side elevation of the machine embodying our invention, showing its application to a keir.

Fig. 2 is a central vertical section of the machine.

Fig. 3 is a plan view thereof.

Fig. 4 is a broken sectional plan on the line 4—4 of Fig. 2, and

Fig. 5 is a detail section on the line 5—5 of Fig. 2.

The machine or apparatus is supported on a suitable platform 10 or the like, from 75 which preferably rises a supporting bracket 11 carrying the reel 12 over which the fabric is rolled when piled or removed from the pile. The reel 12 can be carried by the shaft 9 mounted on the bracket 11 and suitably driven. As the fabric runs over the reel 12 it is delivered through a funnel mouth 14 to the vertically arranged pipe or tube 15, and this is rigidly secured in a sleeve 16 on a light framework 17, the latter having depending parts 18 with lateral arms 19 resting in the open topped brackets 20 of the posts 21. These posts are shown supported on the top of the keir 22 but they can be supported on any other vessel to 90 which the fabric is to be supplied, or in some cases as when the piler is used for piling in a bin or on a floor (in which case it is not necessary to raise and lower it) the posts can be dispensed with and the machine rigidly braced in a fixed position to the platform 10. The particular form of the framework and connection between the pipe and the posts is not important, but a suitable framework should be provided so 100 as to brace the pipe, and it is desirable to have the framework rest in suitable steady-ing supports as described so that for certain uses it can be readily removed from the supports when desired, for the reasons 105 which will presently appear.

Journaled in one of the members 18 and in a parallel bracket 18^a dropped from the frame 17, is a short shaft 23 having a driving pulley 24 or other means of driving, and 110 this can be rotated in any convenient way, as for instance, by the belt 25 connecting with

a pulley on the shaft 9 above. The shaft 23 carries a bevel gear 26 which meshes with a horizontal bevel gear 27, the latter being secured to a sleeve 28 which is arranged on the pipe 15 near the lower part thereof, and it carries a heart-shaped cam 29 which extends horizontally from the sleeve 28 as shown. It will thus be seen that a rotary movement is imparted through the gears 26 and 27 to the cam 29 which revolves on the pipe 15. The shaft 23 also carries a small bevel pinion 30 meshing with a horizontal gear wheel 31 on the sleeve 32 which is arranged inside of the sleeve 28, and is provided with a fixed collar 33, and suitable bearings, preferably anti-friction or roller bearings 34 and 35 are arranged between the collar 33 and the lower end of the sleeve 28, and between the collar 33 and a fixed collar 35^a at the lower end of the pipe 15. The collar 33 has a depending arm 36 which has a knuckle 36^a thereon serving as a pivotal support for the funnel or chute 37 which is arranged below the pipe 15 and serves as a guiding medium to properly guide the fabric to be piled. The funnel or chute 37 is fixed to the oscillating lever 38 which is pivoted as shown at 38^a to the knuckle 36^a, and this lever extends upward and contacts with the edge of the heart-shaped cam 29. Obviously the shape of the cam can be varied, but this shape has been found desirable because it imparts the proper movement to the chute 37.

It will be seen that as the collar 33 rotates it will carry with it the arm 36 and guide chute 37 so that the latter will have a rotary or axial movement, and as it revolves, the free end of the lever 38 riding on the face of the cam 29 will move in and out and so oscillate the chute 37, imparting thereto a movement nearly tangential to its axis so that the fabric which issues from the guide chute will be laid in a pile of a general star shape and with the layers around a central axis. Because of the difference in gearing of the cam and the chute, the oscillations and the revolutions of the chute do not synchronize. Consequently the tangential path of the free end of the chute is advanced at each revolution over the path followed by it in the preceding revolution. Thus during the complete cycle, the free end of the chute traverses minutely every part of the area of an imaginary plane over the space where the fabric is piled and the fabric is therefore evenly distributed. Thus the fabric will not be unduly twisted and tangled, but will be laid evenly in piles running in and out from the center, so that if it is to be treated with liquor, the liquor will have even access to all parts of the fabric, and when the fabric is to be withdrawn it will run smoothly and be unpiled without tangling.

If the fabric is piled in a keir or similar vessel where it is to be treated with liquor, it is the practice to circulate the liquor through the vessel, withdrawing it from the lower part thereof and returning it at the top, and we have shown means for carrying out this usual practice. A hose pipe 39 connects with the lower part of the keir in the usual way or any preferred way, (this is not shown in the drawing because it is the common practice) and at its upper end the pipe connects with a short pipe 40 which delivers into the pipe 15 and thus provides for the return of the liquor, and helps carry the fabric down through the pipe 15. In practice several of these return pipes 39 and connections 40 are used, but one is shown in the drawings.

The upper end of the pipe 15 is held rigidly in a sleeve 41 which is vertically movable in the framework or bracket 43^a connected with the support 10. The sleeve 41 is provided with a rack 42, and this meshes with a worm 43 on the worm shaft 44 which is journaled in the bracket 43^a and the shaft 44 connects by a universal joint 45 with a rod 46 which extends downward and outward and is provided with a wheel 47 by which it can be turned. Thus when the fabric has been piled in a keir or similar vessel, the whole operative apparatus can be raised by turning the worm wheel 43 which will lift the pipe 15, the framework 17, and the operating gears and parts as well as the chute 37, so that the latter can be readily removed from the vessel in which it has been delivering fabric. When the fabric has been treated and is to be removed, it is simply rewound over the reel 12 and withdrawn from the pile.

From the foregoing description it will be seen that we have devised a very simple and practical machine as well as a strong one for doing the work, and obviously many of the details of construction can be changed without affecting the principle of the invention. The important thing is to have the fabric delivered through the guide or distributing chute so as to be piled in even layers running in and out from the center, and preferably in a generally radial or tangential manner, so that all parts can be readily treated, and can be as readily removed without damage. Likewise it will be seen that the machine can be used for piling fabrics on an open floor or in any form of container, as well as in a treating vessel or keir.

We claim:

1. A piling machine comprising a guide or distributing chute, means for rotating the chute and also imparting a movement in and out at a tangent to its circle of rotation, and means for delivering fabric to the chute.
2. A piling machine adapted to deliver

fabric in a pile, and characterized by a distributing or guide chute, means for rotating the chute, means for imparting to the chute a movement in and out with relation to its 5 axis, and means for raising and lowering the chute.

3. A piling machine comprising a rotatable and vertically movable guide chute, means for delivering fabric to the chute, 10 and means for imparting to the chute a swinging movement in and out with relation to its axis.

4. A piling machine comprising a rotatable support, a guide chute, a lever secured 15 to the chute and pivoted on the rotatable support, means for delivering fabric to the guide chute, and means for oscillating the lever whereby the guide chute will be rotated and moved in and out at a tangent to its 20 circular movement.

5. A piling machine comprising a rotatable guide chute, means for delivering material to the chute in a generally radial manner, and means for swinging the guide chute 25 in and out with relation to its axis as the chute rotates.

6. A piling machine comprising a feed pipe, a rotatable support on the feed pipe, a guide chute suspended from said rotatable 30 support and arranged below the feed pipe, a lever connected with the guide chute and pivoted on the said rotatable support, and means for oscillating the lever so as to swing the guide chute in and out in a generally radial manner with relation to its 35 axis.

7. A piling machine comprising a feed pipe, a guide chute rotatably supported below the pipe, means supported adjacent to 40 the pipe for swinging the guide chute in and out with relation to its axis, and means for raising and lowering all the aforesaid mechanism.

8. A piling machine comprising a verti-

cally movable framework, a feed pipe carried by the framework, a rotatable support 45 on the feed pipe, a guide chute carried by the support and arranged below the feed pipe, means for oscillating the guide chute on its support, the means for rotating and 50 oscillating the guide chute being carried by the aforesaid framework, and means for raising and lowering the framework.

9. A piling machine comprising a feed pipe, a rotatable support thereon, a guide 55 chute arranged below the feed pipe, a lever connected to the guide chute and pivoted on the aforesaid rotatable support, a cam rotating around the feed pipe and actuating the said lever to swing the chute in and out 60 in a generally radial manner, and a gear mechanism for operating the rotatable support and the cam.

10. A piling machine comprising a framework removably supported, a feed pipe vertically arranged and carried by the framework, a guide chute rotatably supported on the feed pipe, an oscillating lever connected with the guide chute to move it in and out with relation to its axis, a cam rotating 70 around the feed pipe and actuating the lever, and means for raising and lowering the framework with relation to its supports.

11. A piling machine comprising a vertically movable framework, a vertical feed 75 pipe carried by the framework, a guide chute arranged below the feed pipe, means carried by the feed pipe and framework for imparting a rotary movement and also an oscillatory movement to the guide chute, 80 and a gear and rack mechanism for vertically adjusting the feed pipe framework and parts carried thereby.

CHARLES TAYLOR.

BERTRAM H. SAUNDERS.

Witnesses:

WARREN B. HUTCHINSON,
M. G. O'DONNELL.

It is hereby certified that in Letters Patent No. 1,342,190, granted June 1, 1920, upon the application of Charles Taylor and Bertram H. Saunders, of Paterson, New Jersey, for an improvement in "Piling-Machines," errors appear in the printed specification requiring correction as follows: Page 3, lines 23-24, claim 5, after the word "chute" strike out the words "in a generally radial manner"; same page and claim, line 24, after the word "chute" insert the words *in a generally radial manner*; and that the said Letters Patent should be read with these corrections therein that the same may conform to the record of the case in the Patent Office.

Signed and sealed this 10th day of May, A. D., 1921.

[SEAL.]

T. E. ROBERTSON,

Commissioner of Patents.
